UNITED STATES PATENT OFFICE.

JAMES CLAYTON, OF COVENTRY, ENGLAND, ASSIGNOR TO THE VISCOSE COMPANY,
OF MARCUS HOOK, PENNSYLVANIA, A CORPORATION OF PENNSYLVANIA.

APPARATUS EMPLOYED IN THE MANUFACTURE OF ARTIFICIAL SILK.

1,366,163.

Specification of Letters Patent. Patented Jan. 18, 1921.

Application filed August 26, 1919. Serial No. 320,020.

To all whom it may concern:

Be it known that I, JAMES CLAYTON, a subject of the King of Great Britain, residing at 12 Middlesborough road, Coventry, in the county of Warwick, England, have invented new and useful Improvements in Apparatus Employed in the Manufacture of Artificial Silk, of which the following is a specification.

10 This invention consists in an improvement in, or modification of, the invention for which I have made application, No. 309509, for Letters Patent dated the 8th day of July, A. D. 1919.

15 I have found that the utility of my invention, the subject matter of my said application No. 309509, is improved if I cool the electric motors by which the spindles of the spinning nozzles are rotated to effect 20 additional twisting between the said nozzles and the guides in the setting bath, such cooling not only preserving the motor, but also preventing any injurious effect of the heat of the said motors on the viscose, or 25 the like, employed.

I effect this cooling of the motors by passing air, or causing air to pass through them during their operation and I preferably utilize the standards which support the 30 spindles and pumps, so that, while one serves for the passage of the viscose, or the like, the other serves for the passage of air to the motors, and I further, preferably, provide means for protecting, from 35 viscose, or the like, and acid, these parts and the electric conductors by which current is supplied to the motors.

The accompanying drawing represents 40 what I consider the best means for carrying my present invention into effect, but I do not limit myself to the precise details 45 illustrated.

Figure 1 shows, in elevation partly in vertical section, Fig. 2 in sectional plan and 45 Fig. 3 in section (partly in vertical section) at right angles to Fig. 1, sufficient of the apparatus to illustrate the application of my invention thereto.

The parts which correspond with those 50 shown in the specification of my aforesaid application No. 309509 are marked with the same letters of reference, these parts being the spindle A, nozzles a, bath B, motor f, f², motor-casing G, ball bearings g, viscose-pipe 55 H, for supplying the viscose, or the like,

and the part h, which receives viscose, or the like, on its way, through the spindle, to the nozzle. The viscose, or the like, is presumed to pass from the supply-pipe H, through passages in one (J), of the standards which support the nozzle-spindle A, and pump K, the said standard J, being mounted on the said pipe H, which is perforated to communicate with the passage j², in the said standard, which passage j² is 60 controlled by a valve j³. The viscose, or the like, then passes through the trunnion to, and from, the pump K, by the passage at k, through the filter L, and the other parts which carry the spindle A, of the nozzle, 65 and thence through the nozzle into the bath. The other of the standards (J²) is mounted upon, and a passage j⁴ therein communicates with, a pipe I, into which air is passed, the interior of each motor-casing being put 70 in communication with this pipe I, through the passage j⁴, in the standard j², which passage j⁴, communicates with a passage k², in the trunnion-piece k⁴ of the part L, which passage k², communicates with the 75 space l, in the said part L; air, from the pipe I, passing through these passages j⁴ and k², into the said space l, and thence, by the pipe m, into the casing G, of the motor and between the rotor and stator of 80 the said motor, and out by the opening g². The course of the air is indicated by the 85 arrows.

The motors are fed with electric current from any suitable source through conductors 90 S, which are led through pipes s, to a switch at S², and thence to the stator f of the motor.

To protect the conductors and the parts beneath, I provide a guard-plate T, which may extend along the length of a machine 95 of any number of spindles and has openings in it at t, for the passage and movement of the part L, of the spindle mountings when they are turned, and will allow any viscose, or the like, or acid, deposited 110 thereon to flow off without contaminating the parts beneath, or the conductors.

What I claim is:—

1. In apparatus for spinning viscose or the like, a hollow spinning spindle through 105 which viscose is passed, a motor for driving the same and comprising a rotor on the spindle and a surrounding stator, a casing enclosing said motor and the associated portion of the spindle, and means for passing 110

- a current of air through said casing and between the rotor and stator of the motor.
2. In a construction such as specified in claim 1, a hollow standard upon which the casing and nozzle are pivotally supported, and means for supplying air therethrough to the casing.
3. In a construction such as specified in claim 1, a pair of hollow standards upon which the casing and nozzle are pivotally supported, and means for supplying viscose through one of the standards to the spinning spindle, and means for supplying air through the other standard to the casing.
4. In apparatus for spinning viscose or the like, a setting bath trough, a hollow spinning spindle adapted to dip at its free end into the setting bath in the trough, a casing surrounding the opposite end of the spindle, a motor within the casing for driving the spindle, wire leads arranged below

the casing and connected to the motor therein, a viscose feed pipe also arranged below the casing, and means for delivering viscose therefrom to the spinning spindle, an air pipe arranged adjacent the viscose pipe, and means for delivering air therefrom to the casing to cool the motor, together with a drip pan overlying the wire leads, viscose feed means, and said pipes to protect the same from viscose and setting bath waste, in combination with a standard passing through said drip pan and supporting the spinning nozzle and motor casing above the latter, substantially as described.

In testimony whereof I have signed my name to this specification in the presence of two subscribing witnesses.

JAMES CLAYTON.

Witnesses:

ALBERT BROWN,
ANNIE L. WADE.
